UNITED STATES PATENT OFFICE.

FRANK BUCHANAN, OF DAYTON, OHIO.

HEADLIGHT.

1,143,806.

Specification of Letters Patent. Patented June 22, 1915.

Application filed December 9, 1909. Serial No. 532,245.

To all whom it may concern:

Be it known that I, FRANK BUCHANAN, of Dayton, in the county of Montgomery, in the State of Ohio, have invented new and useful Improvements in Headlights, of which the following, taken in connection with the accompanying drawings, is a full, clear, and exact description.

This invention relates to certain improvements in electric head-lights adapted to be placed upon the dash or front of the cars of electric railways and involves the use of a luminous or flaming arc lamp and a suitable lens associated therewith in such manner as to concentrate the projected rays of light at a greater distance and within a smaller radius or compass ahead of the car than has heretofore been possible with the use of a reflector.

In the ordinary head-light now in common use in which reflectors are employed, it is necessary to place the lamp within the apex of the reflector which not only produces an objectionable diffusion of the projected rays of light over a wider area transversely to the focal axis but throws the more intense rays considerable distances beyond opposite sides of the track along which the car is traveling, leaving a more or less nebulous center directly ahead of the car and necessitating the use of extra "dimming" devices particularly when the car is passing through the more thickly populated districts.

Another objection to the use of reflectors particularly in connection with the luminous arc lamps on the cars of double tracked railroads is the "blinding" effect of the most intense laterally deflected rays of light upon the operators or occupants of an approaching car or other road vehicles or upon approaching pedestrians.

The main object of my present invention is to avoid the use of reflectors and their attendant disadvantages and at the same time to project a more intense light from an electric flaming arc lamp a greater distance ahead of the car and to confine the projected rays within a smaller area and more nearly within the track along which the car is traveling. In other words I have sought to associate a special form of lens with an electric flaming arc lamp in such manner that the light of greatest intensity from the luminous arc or flame will be projected un-

obstructed a greater distance ahead of the car and within a less area than would be possible with the use of a reflector.

Another object is to enable the lamp to be adjusted relatively to the lens, so as to bring the metallic flame in proper relation to the focal point of the lens.

A further object is to provide for the use of one or more incandescent lamps located near the focal point and above the focal axis of the lens, so as to throw an effective but very much subdued light downwardly in oblique rays upon the track and ahead of the car when traveling through cities and other congested districts.

Other objects and uses will be brought out in the following description:

In the drawings Figure 1 is a front elevation of a head-light embodying the various features of my invention. Fig. 2 is a transverse vertical sectional view of the same head-light showing the arc and incandescent lamps in elevation. Fig. 3 is an elevation of the meeting ends of the electrodes of the arc lamp.

In carrying out the objects stated, I provide a suitable inclosing case —1— with a front door —2— which is held in place by hinged connections —3— and removable pivotal bolts —4— either of which latter may be removed to permit the door to be swung on the opposite hinge. Centrally mounted in this door is a circular signal or Fresnel lens —5— of predetermined focus, having an outer convex face —6— and an inner but smaller convex surface —7— the latter being surrounded by a series of concentric stepped planes or annuli —8— the purpose of which is to concentrate the projected rays within a much smaller area. Mounted with in the inclosing case —1— upon a sliding shelf or base —9— is an upright support or bracket —10— carrying a pair of vertically disposed flaming arc electrodes —11— and —12— similar to those set forth in my pending application No. 523,579, filed October 20, 1909, for producing a luminous arc —13— Fig. 3. The lower electrode —11— is mounted upon a vertically movable rock arm —14— in such manner as to remain substantially vertical in all positions of adjustment and is normally held in contact with the upper electrode when the arc light is not in use by weighted lever —15— and suitable connections between said weighted lever and

rock arm. The weighted lever —15— is connected to the armature of a solenoid —16— which is connected in the arc lamp circuit, as shown in my pending application referred to, so that when such circuit is closed the electrode —11— will be withdrawn from contact with the upper electrode —12— to form the flaming arc light —13—. This lower electrode preferably consists of a metallic tube containing a comminuted substance such as titanium or equivalent material for producing in conjunction with the upper electrode —12— a luminous arc. The upper electrode —12— which is made of suitable metal is adjustably mounted within an upright ventilating tube —17— and held in its adjusted position by a set screw —18—.

The metallic electrodes are so arranged that their opposing ends are near the focal axis and also the focus of the lens, and thus the luminous flame between such electrodes is substantially at the focus of the lens and the rays of light from such flame are refracted by the lens into a beam of substantially parallel rays. Heretofore it has been proposed to use other forms of electrodes as carbons in connection with Fresnel lenses but as a great part of the luminosity of the lamps is caused by the incandescence of the points of the carbons it is impossible to bring both luminous points within the focus or focal axis of the lens. I have discovered that flame or metallic arc lamps are particularly adaptable to be arranged so that the point of greatest luminosity of the arc can be located substantially at the focus of the Fresnel lenses and thus a beam of much greater length and intensity is projected by the lenses than by the use of any other form of electrodes.

The adjustment of the electrodes along the focal axis of the lens relatively to the focal point of the lens may be effected by simply opening the door —2— and adjusting the sliding base —9— forwardly or rearwardly as may be desired to bring the flame —13— at the focal point or to the front or rear thereof. The maximum intensity of light is produced by bringing the flame slightly in front of the focal point of the lens or in such position that the ends of the flame will coincide with lines drawn from such focal point to the margin of the lens. If, however, the flame is moved farther forward or to the rear of the focal point, the intensity of the projected rays of light will be very much subdued owing to certain aberrations of reflection and refraction or to the inharmonious relation of the lens and source of light which is well understood in the art of light reflecting and refracting mediums. Any suitable means may be provided for holding the sliding base and parts mounted thereon in their adjusted position and for the purpose I have shown a spring detent

—9'— having a plurality of shoulders for engaging the front portion of said base. In some instances particularly when the car is traveling long distances through cities, it is desirable to conserve the electric energy of the flaming arc lamp and at the same time to produce an effective but subdued light and for this purpose I provide one or more, in this instance two, incandescent lamps —19— which are mounted upon a superposed bracket —20— above and at opposite sides of the focal axis, as —a—, of the lens so as to cause the rays of light therefrom to be projected downwardly and obliquely through the lens upon the tracks directly ahead of the car said bracket —20— being secured to the front side of the tube —17—.

The metallic flame is more or less susceptible to being snuffed out by excessive air drafts and in order to avoid that objectionable result and at the same time to provide for proper ventilation of the heated air and gases from the interior of the case, the marginal edges of the door are spaced a slight distance apart from the adjacent edges of the main body of the case —1— by spacing members —22— so as to leave an intervening space —21—.

In constructing this head-light, the lens and case are assembled and related so that the focal point of the lens will fall within the case and substantially coincident with the meeting ends of the metallic electrodes thereby bringing the metallic flame at or near such focal point. I am aware that lenses of this character have been used in connection with oil lamps for signaling and semaphores but I believe that I am the first to combine such lens with a flaming arc electrode both mounted upon or within a case the entire combination to be used as a head-light capable of projecting its rays of light a much greater distance ahead of the car and within a much smaller radius transversely of the axis than would be possible with the use of a reflector even with the same electrodes.

What I claim is:

1. A headlight comprising a casing, a lens arranged in said casing and constructed to refract the rays of light into a beam, a vertically disposed substantially non-consuming anode arranged above and contiguous to the focal axis of the lens, and a cathode of slow-consuming material vertically disposed directly beneath the anode and with its upper end below and contiguous to the focal axis of the lens, said cathode furnishing an arc stream giving the major portion of the illumination of the arc, and said stream being located in the focal axis of the lens and at the focal point thereof, substantially as and for the purpose described.

2. An electric head light having upper and lower electrodes, a draft tube, and an incan-

descent electric lamp supported by the draft tube, substantially as and for the purpose described.

3. An electric head light comprising a fixed upper electrode and a movable lower electrode, a draft tube inclosing the upper electrode and having means for supporting the same, and an incandescent electric lamp supported by the draft tube, substantially as 10 and for the purpose specified.
4. In an electric head-light, comprising a

casing having a glass front, vertically disposed electrodes within the casing, a tube supporting the upper electrode and incandescent lamps supported by said tube. 15

In witness whereof I have hereunto set my hand on this 24th day of November, 1909.

FRANK BUCHANAN.
